UNITED STATES PATENT OFFICE.

FRANK J. DUTCHER, OF HOPEDALE, MASSACHUSETTS, ASSIGNOR TO DRAPER COMPANY, OF HOPEDALE, MASSACHUSETTS, A CORPORATION OF MAINE.

LOOM-SHUTTLE.

1,098,713.

Specification of Letters Patent.

Patented June 2, 1914.

Application filed October 6, 1909. Serial No. 521,306.

To all whom it may concern:

Be it known that I, FRANK J. DUTCHER, of Hopedale, Worcester county, Massachusetts, have invented certain new and useful 5 Improvements in Loom-Shuttles, of which the following is a specification.

The present invention relates to the weft-carrier holding springs of shuttles used in automatic weft-replenishing looms wherein 10 replenishment is effected by ejecting the spent weft-carrier from the shuttle and inserting a fresh weft-carrier.

It is old to employ for holding the weft-carrier a spring consisting of two independent 15 resilient jaws which grasp the butt of the weft-carrier on opposite sides; and the present improvement consists in the means employed for maintaining such independent jaws in proper relative position.

20 The improvement is illustrated in the accompanying drawings wherein—

Figure 1, is a plan view of one end of a shuttle having one form of the improved spring. Fig. 2, is a perspective of the 25 spring shown in Fig. 1. Fig. 3, is a perspective of the shanks of a second form of spring. Fig. 4, is a similar perspective of a third form. Fig. 5, is a section of the shanks of a fourth form. Fig. 6, is a side view of 30 the form shown in Fig. 5.

As shown in Figs. 1 and 2, the weft-carrier holding shuttle spring comprises two independent grasping jaws A, and B, having respectively shanks a, and b, which are 35 in contact with each other and fit a recess in the shuttle C, in the usual manner secured to the shuttle, as customary, by a bolt D, passing through holes e, in the shanks. It is vital that the two jaws should not turn on 40 the bolt D, independently of each other, but should be locked one to the other. To this end the shank a, of jaw A has an extension d, which is folded around the square inner end of the shank b, of jaw B, and through 45 this folded extension the bolt D, also passes. The two jaws are thus mutually directly engaged and locked together so that one cannot turn on the bolt independently of the other.

50 In the form shown in Fig. 3, the shank b, of jaw B, has a right-angled open recess e, at its inner end, in which fits a rectangular stud f, bent and projecting laterally from the inner end of the shank a, of jaw A.

In the form shown in Fig. 4, the shank b, 55 of jaw B, has a right-angled stud g, projecting beyond its inner end which is straddled and fitted by two flat faced fingers h, h, stud f, bent and projecting laterally from the shank a, of jaw A. 60

In the form shown in Figs. 5 and 6, the shank b, of jaw B, has a plurality of recesses i, surrounding the bolt hole e, which may extend either partly or all the way through the shank, both ways being shown 65 in Fig. 5, the recesses being, however, on the inner face of the shank. The shank a, of jaw A, on its inner mating face has a plurality of correspondingly located laterally projecting studs t, which closely fit the recesses i, respectively. 70

In each of the several forms the two jaws are directly and mutually locked together by co-acting integral and reciprocal provisions. 75

I claim:

1. A loom shuttle having a weft-carrier holding spring consisting of two separate and independent spring jaws having shanks which seat against each other and are directly and mutually locked together by co-acting integral provisions. 80

2. A loom shuttle having a weft-carrier holding spring having two separate and independent spring jaws having shanks which seat against each other and are locked together by mutually engaging integral projections and recesses. 85

3. A loom shuttle having a weft-carrier holding spring consisting of two separate and independent spring jaws mutually locked together by coacting integral provisions. 90

4. A loom shuttle having a weft-carrier holding spring having two separate and independent spring jaws locked together by mutually engaging integral projections and recesses. 95

In witness whereof, I have hereunto signed my name in the presence of two subscribing 100 witnesses.

FRANK J. DUTCHER.
